UNITED STATES PATENT OFFICE.

GRAHAM MCKINNON, OF ROWLAND, NORTH CAROLINA.

BED-PAN.

1,178,453.

Specification of Letters Patent.

Patented Apr. 4, 1916.

Application filed December 12, 1914. Serial No. 876,904.

To all whom it may concern:

Be it known that I, GRAHAM MCKINNON, a citizen of the United States, residing at Rowland, in the county of Robeson and 5 State of North Carolina, have invented new and useful Improvements in Bed-Pans, of which the following is a specification.

The present invention relates to improvements in the construction of bed pans, and 10 an object of the invention is to provide a pan which shall be sustained when arranged in an opening in a mattress provided therefor.

With the above and other objects in view, 15 the improvement resides in the construction, combination and arrangement of parts set forth in the following specification and falling within the scope of the appended claims.

In the drawing: Figure 1 is a perspective 20 view of a mattress constructed in accordance with the present invention showing the bed pan in position thereon, Fig. 2 is a central longitudinal sectional view through the same, Fig. 3 is a perspective view of the bed 25 pan, and Fig. 4 is a perspective view of the block or filler member for the opening in the mattress.

Referring now to the drawing in detail, the numeral 1 designates a mattress of the 30 ordinary construction but which is provided at a suitable point therein with a round opening 2.

The numeral 3 designates a filler member or plug which is adapted to be received 35 within the opening to complete the mattress, the said block conforming to the shape of the opening and frictionally engaging with the side walls provided by the said opening to sustain the same in proper position upon the mattress.

The mattress is primarily adapted for use in hospitals or in sick rooms and the plug 3, while frictionally engaging with the walls of the opening 2 of the mattress 1, may be 45 readily removed therefrom and a bed pan 4 arranged within the said opening. The bed pan 4 comprises a body portion conforming to the shape of the opening 2 and is of a depth corresponding approximately to the

thickness of the mattress. The bed pan is 50 provided upon its open upper surface at one of its ends with an upwardly projecting lip 5, the said lip having its edges from its central portion gradually converging to the upper and beaded open top of the pan 4. 55 Arranged diametrically opposite the lip 5 upon the upper and lower edges of the pan 4 are longitudinally extending flat substantially rectangular members or cleats 6 and 7 respectively. These cleats 6 and 7 are so 60 arranged as to engage with the upper and lower surfaces of the mattress 1, while positioned upon the upper beaded edge of the bedpan opposite the terminal of the edges of the lip 5 with the said bead are downwardly extending eye members 8, one being arranged diametrically opposite the other and both being adapted to receive the hook ends of a handle or bail 9.

From the above description, taken in connection with the accompanying drawing, the simplicity of the device, as well as the advantages thereof will, it is thought, be perfectly apparent to those skilled in the art to which such invention appertains without 75 further detailed description.

Having thus described the invention, what I claim is:

1. A bed pan including a body portion having one of its ends formed with an angular lip which is inclined to the mouth of the pan, a bail for the pan, said pan being provided with longitudinally extending upper and lower cleats.

2. A bed pan including a body member 85 having a beaded top, an angular lip arranged upon the beaded top to one end of the pan and having its sides inclined gradually to the said beaded top of the pan, said pan diametrically opposite the bead being 90 provided with upper and lower cleats, as and for the purpose set forth.

In testimony whereof I affix my signature in presence of two witnesses.

GRAHAM MCKINNON.
